UNITED STATES PATENT OFFICE.

CLINTON E. WILDER, OF IRVINE, PENNSYLVANIA.

CENTRIFUGAL PIPE MOLD.

Application filed October 23, 1923. Serial No. 670,329.

To all whom it may concern:

Be it known that I, CLINTON E. WILDER, a citizen of the United States, residing at Irvine, in the county of Warren and State 5 of Pennsylvania, have invented certain new and useful Improvements in Centrifugal Pipe Molds; and I do hereby declare the following to be a full, clear, and exact description of the invention, such as will enable 10 others skilled in the art to which it appertains to make and use the same, reference being had to the accompanying drawings, and to the letters of reference marked thereon, forming part of this specification.

15 This invention relates to improvements in the construction of mold tubes for centrifugal casting machines, in which machines the mold tube is rotated at a high rate of speed while a stream of molten metal is introduced 20 therein in a suitable manner.

Heretofore it has been the practice to construct the mold tubes for centrifugal casting machines of sufficient wall thickness to ensure the mold tube retaining accurate alignment which necessitates a wall substantially one and one-half inches thick. This mold tube is placed in an enclosing jacket spaced therefrom, and mounted in suitable bearings, and provided with mechanism adapted to 25 cause the mold tube to rotate rapidly within said jacket, and there is provided a means to circulate water in the space between said jacket and mold tube to keep the mold tube cool, as shown in U. S. patent to De Lavaud 30 No. 1,398,008.

35 I have found from practice that with the thick walled mold tube considerable time is required for the thick wall of mold tube to cool, after being heated by the molten metal, owing to the resistance of the thick, heated, mold tube to the transference of cold from the water jacket to the layer of hot metal which has been cooled sufficiently to shrink 40 loose from the mold tube and be withdrawn 45 therefrom.

The object of this invention is to overcome the difficulties incident to the use of a thick walled mold tube in a casting machine. I overcome these difficulties by providing a 50 comparatively thin,—say one half of an inch in wall thickness—lining for the ordinary thick mold tube, spacing this lining away from the interior surface of the thick mold tube, and providing, at longitudinal 55 intervals along the length of said lining tube, elastic metallic bands having project-

ing radially therefrom studs adapted to engage the interior surface of said thick walled mold tube to support said thin walled liner, and between said elastic metal bands the 60 space between the liner and the thick mold tube I insert rope-shaped sponge-like material adapted to partially fill said space and become absorbed with water and at the same time permit the water to gradually flow longitudinally through the space between said thick mold tube and said liner. The water for cooling the thin lining is admitted from the usual water jacket through holes in the wall of the thick mold tube along its smallest 65 diameter, and flows therefrom back into said jacket through holes in the wall of the thick mold tube at its greatest diameter, thus causing a continuously moderate longitudinal circulation of cooling fluid through the space 70 between said tubes without causing the liner to become checked or otherwise injured, the cooling medium in the space becoming sufficiently heated to prevent injury to the cast metal, and yet preventing the thin liner 75 from becoming injured. The thin wall of the liner presents so little resistance to the transference of cold from the cooling medium to the cast metal, that it is quickly cooled 80 sufficiently to be removed from the liner. 85

These and other features of this invention will be hereinafter set forth and pointed out, and are illustrated in the accompanying drawings in which:

Figure 1 is a longitudinal section of a 90 mold tube and liner therein, according to my invention.

Figure 2 is a transverse section thereof on the line 2—2 in Fig. 1.

Figure 3 is a transverse section of the 95 same on the line 3—3 in Fig. 1.

Figure 4 is a transverse section of the same on the line 4—4 in Fig. 1.

In these drawings A indicates the ordinary thick mold tube as ordinarily used 100 in a centrifugal casting machine, and as ordinarily used in a machine of the De Lavaud type, receives the molten metal directly upon its interior, while in this invention the thick tube A serves only to support, in true alignment, the comparatively thin lining tube B, which in reality is the mold tube of the 105 structure.

The thick mold tube A is provided with 110 series of holes *a* at the small diameter of the tube, as at the cross-section 4—4 (see Fig. 4). Said holes are at an angle through

the wall of the mold tube A, so that when the tube revolves in the direction of the arrow in Fig. 4, they tend to scoop in water from the water jacket, (not shown) of the machine, in which the tube revolves. There are preferably several series of these holes *a* along the length of the tube, while at the largest diameter of the mold tube A is a series of holes *a'* at the cross section line 2-2 in Fig. 1, see Fig. 2, which are inclined backward from the direction of revolution of the tube A so that they will not scoop in water from the water jacket (not shown) and being at a greater diameter tend to throw the water out of the holes *a'* and thus create a circulation of water longitudinally through the space between the tubes A and B.

In the space between the tubes A and B are placed at intervals, narrow flexible metallic rings C having radial studs C' which are adapted to support the thin liner tube B in true alignment with the tube A, see Fig. 3. These rings C are parted, as at 25 *c*, and the radial studs C' are preferably slightly short of the exact diameter of the tube A, so as to allow for the expansion of the tube B during the pouring of the molten metal thereinto. Thus it will be seen 30 that the thin lining tube B will be perfectly supported by the thick outside tube A, and prevented from becoming out of alignment.

The space between the tubes A and B between the elastic metallic rings C is filled 35 with coiled wire D, the several coils D being interlaced as shown in Figs. 2 and 4, so that they will form a band of coiled wire around the tube B between the rings C. The 40 diameter of the coils D is equal to the width of the space between the tube A and the tube B.

Into the several coils D I place material 45 capable of absorbing water and resisting heat. I have found that asbestos rope is well adapted for this purpose. This asbestos material fills the interior of the wire coils, but leaves spaces *d* between the wire coils on the walls of the tubes A and B, and between the coils D through which water can 50 circulate longitudinally of the tube A. These wire coils D, thus filled with a porous material D' acts to keep the thin tube B in alignment between the rings C, and 55 serves to retard the longitudinal flow of water through the space between said tubes, so that the water becomes sufficiently hot enough to prevent over chilling of the casting, and at the same time prevents injuring the tube B. The difference in temperature 60 between the water in the space between the tubes A and B will be readily transferred through the thin tube B to the layer of hot metal thereon to cause it to cool sufficiently to shrink away from the mold tube

B so that it can easily be withdrawn therefrom.

The outer tube A is provided with an annular shoulder E against which the outturned flange E' on the tube B engages, and from the shoulder E screw threads F are provided in the outer tube, which engage threads on a ring G which screw into the end of the tube A and force the flange E' securely against the annular shoulder E. 75

At the opposite end of the tube A is an inturned annular flange H against which the coils D and rope filler D' abut, while the inner tube B extends through the flange H and through a gland-ring H' which 80 presses against suitable packing *h* to seal the joint between the tube B and flange H.

Secured to the outer tube A are tap bolts J upon which a ring K is placed which is adapted to engage the end of the tube B. 85 and on the tap bolts springs J' and nuts J² are placed so that the springs J' press against and force the ring K against the tube B with a yielding pressure so as to compensate for the longitudinal expansion 90 of the inner tube B.

In use, this outer tube A and lining tube B are inserted into a molding machine of the type shown and described in U. S. Patent No. 1,398,008, hereinbefore referred 95 to, in the usual manner and the water jacket therein filled with water in the usual manner, so that when the mold tubes herein described are rotated, water from the water jacket enters into the space between the outer thick tube A and the inner liner tube B through the holes *a* in the wall of the tube A and saturates the asbestos filler in the coiled wire centering supports D, and is caused to longitudinally circulate thereabout and therethrough by reason of the difference in diameter of the tube A where the intake holes *a* and the outlet holes *a'* pierce the wall of said tube, so that the outside of the thin mold tube B is at all 100 times surrounded by a hot moist layer of heat proof material with sufficient circulation to carry off the burning heat of the molten metal, and thereby prevent the burning of the tube B, so that the same will 105 not become checked on its inner surface, and will not become sufficiently chilled to injure the surface of the cast metal. The thin wall of the tube B, offers little, if any, 110 resistance to the transference of heat from the cast metal to circulating cooling water in the space between the two tubes A and B, and which is carried off thereby. 115

As the pouring spout recedes, and the molten metal is laid upon the inner surface of the rotating mold tube B, always upon a portion which has been cooled by the slowly circulating cooling fluid, said fluid becoming thereby heated as it travels 120 forward over that portion of the mold tube 125

upon which the hot metal has been deposited, so that while the incoming cooling fluid maintains the succeeding portion of the mold tube in a cool condition to receive 5 the metal deposited thereon, the cooling water at the point receiving the hot metal becoming sufficiently heated to cause the molten metal to cool slowly so as not to become chilled, and at the same time owing 10 to its circulation, to carry off the heat rapidly from the cast metal. The wall of the tube B, being thin does not absorb much heat from the molten metal, and the heat thus absorbed thereby is quickly carried 15 off from the cast metal by the cooling fluid.

The mold tube B, not absorbing much heat, its expansion is correspondingly reduced, so that the initial diameter of the cast metal is correspondingly reduced, so 20 that the contraction of the cast metal as it hardens is relatively greater than the contraction of the tube B, so that an air space progressively forms between the cast metal and the tube B, which space progresses 25 longitudinally until the casting is finished.

During this progressive casting operation the cooling medium between the tubes A and B becomes heated sufficiently to prevent the contraction of the tube B, but still retains a 30 sufficient difference in temperature to carry off the heat from the cast metal to cause the required amount of contraction to enable it to be easily withdrawn from the mold tube.

Because the mold tube B, being comparatively thin, is easily kept cool the machine does not have to stand idle to permit the casting to shrink sufficiently to be withdrawn, or for an overheated mold tube to cool.

Having thus described my improved molding tube for centrifugal casting machines, so that others will be able to utilize the same, I do not desire to be limited to the exact construction thereof herein shown and described, as it is evident that many modifications can be made therein without departing from the scope of my invention, therefore what I claim as new and desire to secure by Letters Patent is:

1. A mold tube having a comparatively thin wall, another tube having a thick wall enclosing said mold tube and spaced therefrom, elastic means surrounding said mold tube and contacting with the inner surface 55 of said thick outer tube and adapted to maintain all portions of said mold tube concentric with the inner wall of said thick outer tube, and means to cause a longitudinal circulation of water between said tubes.

2. A mold tube having a comparatively thin wall, another tube having a thick wall enclosing said mold tube and spaced therefrom, elastic means surrounding said mold

tube and contacting with the inner surface 65 of said thick outer tube, and adapted to maintain all portions of said mold tube concentric with the inner wall of said thick outer tube, and means to cause a longitudinal circulation of water between said tubes, asbestos material filling between elastic means to retard said circulation.

3. In a mold tube having a comparatively thin wall, another tube having a comparatively thick wall enclosing said mold tube and spaced therefrom, a series of corrugated metallic rings surrounding said mold tube, spaced at intervals, radial studs formed on said rings and adapted to engage the inner surface of said outer tube, means to cause a longitudinal circulation of water through the space between said tubes, and means to retard the flow of said circulation.

4. In a mold tube having a comparatively thin wall, another tube having a comparatively thick wall enclosing said mold tube and spaced therefrom, longitudinally interlaced coiled wires engaging the outer surface of the thin mold tube and the inner surface of the thick outer tube and adapted to maintain the mold tube longitudinally concentric with said outer tube, asbestos material extending through each of said wire coils, and means to cause water to longitudinally circulate through the annular 95 space between said tubes.

5. In a mold tube having a comparatively thin wall, another tube having a comparatively thick wall enclosing said thin tube, said thick walled tube being of greater 100 diameter at one end than at the opposite end and having openings at intervals along the length thereof, means to maintain the mold tube concentric within said thick outer tube, means to cause water to longitudinally circulate through the annular space between said tubes, and means to retard said circulation.

6. In a mold apparatus, an inner mold tube having a thin wall, an outer tube enclosing said mold tube and adapted to support the same, a plurality of corrugated metallic rings placed at intervals on said inner tube and adapted to engage the inner surface of said outer tube to concentrically support said mold tube within said outer tube, interlaced coiled wire around said mold tube between said corrugated rings of a diameter to engage the outer surface of the mold tube and the inner surface of the thick outer tube adapted to concentrically support said mold tube within said outer tube between said corrugated metallic rings, and asbestos ropes inserted longitudinally 120 through said interlaced wire coils.

In testimony whereof I affix my signature.

CLINTON E. WILDER.
